UNITED STATES PATENT OFFICE.

RICHARD D. GALLAGHER, OF CHICAGO, ILLINOIS.

ADJUSTABLE RAIL CLAMP.

Application filed March 3, 1922. Serial No. 540,745.

To all whom it may concern:

Be it known that I, RICHARD D. GALLAGHER, a citizen of the United States, residing at Chicago, in the county of Cook and State of Illinois, have invented certain new and useful Improvements in Adjustable Rail Clamps, of which the following is a specification.

My invention relates to rail clamps and particularly to clamps suitable for securing railroad rails and the like, to supports along ash-pits and drop-pits, on bridges, and similar structures.

An object of the invention is to provide an adjustable rail clamp arranged to afford clearance for wheel flanges.

Another object of the invention is to provide rail clamps which will rigidly brace rails and which will permit limited lateral movements of the rails so as to adjustably position the same for proper alignment without disturbing the spikes or other fastening means.

A further object of the invention is to provide rail clamps including members having inclined double faced wedge surfaces for securing quick and positive adjustment of the several parts.

Another and further object of the invention is to provide rail clamps having co-operating members, each of which is provided with a plurality of surfaces which are inclined to the horizontal and which intersect the plane of the base of the track rail in lines parallel to the rail base.

A still further object of the invention is to provide a rail clamp that may be easily applied and removed, and which is designed for the severest kind of service, and which may be economically manufactured.

A yet further object of the invention is to improve rail clamps for general successful commercial use.

The above recited and other objects of the invention will be apparent from the following description and drawings and will be particularly pointed out in the appended claims.

Generally speaking, I carry out the preferred embodiment of the invention by providing a rail clamp having clamp tie plates arranged to underlie a rail and provided with shoulders at or near each end of the plate, rail braces adapted to engage the tie plate shoulders and to contact some portion of the rail and wedge blocks adapted to

cooperate with the braces for securing the rails to the clamp tie plates, and means such as bolts for operably effecting the co-operation of the several elements. The braces and blocks have at least two similarly inclined surfaces which are parallel and in different planes.

In the drawings:

Figure 1 is a perspective elevational view 65 of the preferred embodiment of the invention.

Figure 2 is a perspective elevational view 70 of the clamp tie plate employed.

Figure 3 is a perspective view of the pre- 75 ferred rail brace.

Figure 4 is a perspective view of the pre- 80 ferred wedge block.

Figure 5 is a perspective view of a rail 85 clamp embodying my invention, and shown as applied to a track rail and a guard rail.

Figure 6 is a perspective view of the 90 clamp applied to a rail supported in a rail trough such as used on some bridges and the like, and employing suitable insulation for the tie plate.

Figure 7 is an elevational view of the 95 form of tie plate employed in the arrangement of Figure 6.

Figure 8 is a vertical view partially in 100 section of the arrangement of Figure 6; and

Figure 9 is a vertical view partially in 105 section of a rail showing one of the means of applying a guard rail to a track rail carried in a rail trough such as that illustrated in Figure 6.

Figure 10 is a top plan view of the brace 110 shown in Figure 9.

The form of clamp disclosed in Figure 115 is that suitable for ash-pits and drop-pits and is employed for securing rails alongside such pits for purposes well understood. A portion of the foundation 10 is covered with an inverted structural shape such as

a channel 11 on which the rail A is carried. The rail clamp as applied in this form of 120 the invention comprises a clamp tie plate 12 having shoulders 13 and 14 at each end thereof, an opening through the body as

at 15 for the reception of a spike, bolt or 125 other securing means, and another opening 16 through which the clamp bolt passes. A rail brace shown in Figure 3 having the

form illustrated includes a surface 18 substantially that of the contour of the web 130 of the rail, a bottom 19, a notch 20 and an upwardly inclined under surface 21. The

brace has also two inclined surfaces 22 and 23 which are in parallel planes inclined to the horizontal and cutting the plane of the base of the track rail in lines parallel to the rail base. An elongated opening 24 extends through a portion of the brace, lugs 25 and 26 are formed on the brace for the purpose of cooperating with similarly arranged recesses on the wedge block for preventing turning of the same with respect to the brace. The wedge block is shown in Figure 4 and has two inclined surfaces 27 and 28 also inclined to the horizontal and cutting the plane of the rail base in lines parallel to the rail base, an elongated centrally disposed opening 29 and a foot 30. The inclined surfaces 27 and 28 of the wedge blocks are provided with recesses 31 which co-operate with projections or lugs 25 and 26 on the rail braces.

A bolt 32 may be suitably secured in the foundation 10 and in such position as to project through the opening 16 in the clamp tie plate when the same is spiked or otherwise fastened in place. In applying the clamp of the arrangement of Figure 1, tie plate 12 may be secured in position by a bolt, spike or other member passing through the opening 15 in the same and suitably embedded in the foundation 10. The rail A is then placed on the plate and moved against the inner shoulder 13. In this form the shoulder 13 is shown as hooked so as to overlie a part of the base of the rail to prevent tipping of the same in service. The rail brace of Figure 3 is placed in position as shown in the drawings with the curved surface 18 against the web of the rail, and is so positioned that the notch 20 will rest against the base of the rail opposite to the hooked shoulder 13. The wedge block shown in Figure 4 is then applied over the bolt with the foot 30 against the inner surface of the shoulder 14 and with the two inclined surfaces 31 and 28 in contact with the similarly inclined surfaces 22 and 23 of the brace. A nut 33 is then applied to the bolt and tightened; whereupon the several parts will function to force the rail brace against the rail in such manner as to secure the same between the inner shoulder 13 and the rail brace 17.

It will be observed that the inner side of the rail, that is the portion shown at the left in Figure 1, is free from projections, thus affording ample clearance for wheel flanges, and offering no projections for catching ashes or other dirt which might otherwise accumulate and cause derailment. By reason of the double inclined surface contact between the wedge block and rail brace, lateral movement of the rail may be accomplished for purposes of alignment by turning nut 33 with suitable wrench. In the form shown in Figure 5 the clamp tie

plate 34 is secured by means of spikes or other fastenings cooperating with notches 38 at the ends of the plate. This plate is provided with shoulders 36 and 37 at or near the ends of the same, the distance between the shoulders being sufficient to receive a track rail B and a guard rail C together with the necessary clamps for retaining the rails in position. In this form two rail braces and two wedge blocks are employed and arranged as shown in Figure 5. For suitably spacing the rails B and C I provide a separator comprising two similar members 39 and 40 arranged in reverse order, having faces adapted to abut the webs of the rails and other faces which are inclined and which are preferably provided with interengageable portions 41 for preventing relative displacement of these members when once properly positioned. Each of these members may be provided with a downwardly extending tongue 42 for projecting into the space between the bases of the rails. Bolts 43 pass upwardly through suitable openings in the ties 35 and tie plates 34 and the rail braces and wedge blocks. Nuts 44 when applied to the ends of the bolts lock the wedge blocks, with respect to the rails and braces, so as to properly align the rails; by providing braces on each side of the rails lateral movement of the rails may be effected for purposes of alignment without having to withdraw the spikes from the tie plates.

In the form of the clamp shown in Figure 6 a rail D is shown supported in a rail trough, which construction is employed in many instances on bridges, a trough being provided for each rail of the track way. In this form the tie plate 45 has shoulders 46 and 47 at the ends thereof for cooperation with the rail braces and blocks. For securing the tie plates to the bridge structure, bolts 49 are arranged to pass through suitably disposed openings in the bridge structure and correspondingly arranged openings in the tie plates. A lower cross member 51 may be used to underlie the bridge work for purposes of greater rigidity. Where it is desirable to insulate tie plates on the bridge work, I provide a layer of insulating material 50 between the bridge work and the tie plate 45, and also another layer 53 between the lower arm 51 and the under side of the bridge work. Openings 48 in the bridge work through which the bolts pass are preferably made larger than the bolts and in these openings ferrules of insulating material may be inserted as shown in Figure 8. In this manner the tie plate and the rails are insulated completely from the bridge structure and any tendency of the rail to tip does not in any manner affect the insulating material employed.

The clamp used in this form comprises two

rail braces and two wedge blocks as illustrated. These are placed in position and tightened in the manner described hereinabove. It will be noted that this form of tie plate permits alignment of the rail, as loosening one of the bolts on one side and tightening the other will cause lateral movement of the rail to proper position.

In Figure 9 I have illustrated one manner of applying a guard rail 56 alongside of the track rail D in a rail trough such as that shown in Figure 6; the same tie plate 45 with its several attaching means is employed. Instead of making the rail brace as shown in Figure 3 of the drawings I make it as shown in Figure 9. The brace includes shoulders 57 and 58 for contacting the under side of the head and the top of the base respectively, and is provided with a pair of flanges 59, which are separated from the main portion of the brace by a cut out portion 60. The guard rail 56 is in the form of an angle bar with one of the legs of the bar extending downwardly into the slot 60 in the rail brace. At each side of the brace there are outstanding lugs 61 having openings 62 therethrough so that bolts 63 may fasten the guard rail in position on the rail brace. Between the flanges 59 of the brace there are provided inclined surfaces 64 and 65 which are similar in every respect to the faces 22 and 23 of the brace shown in Figure 3 of the drawings. A wedge block such as that shown in Figure 4 and indicated at 66 is employed for forcing the brace firmly against the track rail D in the manner described with respect to the other figures of the drawings.

It will be noted that the clamp of my invention is one which effects clamp engagement of rails on supports by means of members having cooperating inclined surfaces which are in parallel but different planes. These members are so arranged with respect to the tie plates employed as to permit a limited lateral movement of the rails on the plates without having to remove the spikes or other fastening means used to fasten the tie plates to ties and the like. A slight turn of any of the nuts of the clamps of the invention will effect proper lateral movement of the rails.

While I have described more or less precisely the details of construction of my invention, I do not wish to be understood as limiting myself thereto as I contemplate changes in form and proportion of parts and the substitution of equivalents as circumstances may suggest or render expedient without departing from the spirit of my invention.

I claim:

1. A clamp for securing rails to ties comprising co-operating clamping members, some of said members having a plurality of surfaces inclined to the horizontal and ar-

ranged in parallel and different planes which surfaces co-operate to cause wedging action of certain of said members for clamping purposes.

2. A rail clamp, including in combination, a clamp tie plate, a rail brace, a wedge block, and means passing through said tie plate, brace and block for effecting cooperating clamping engagement of said parts with a rail. 75

3. A rail clamp, including in combination, a clamp tie plate, a rail brace, a wedge block, and means passing through the tie plate, brace and block for effecting cooperating clamping engagement of said parts with a rail and a support. 80

4. An adjustable rail clamp, including in combination, a member for engaging a rail support, a rail brace, and a wedge block, and a bolt passing through said member, said block and said brace for effecting clamping engagement of said parts with a rail. 85

5. An adjustable rail clamp, including in combination, a member for engaging a rail support, a rail brace, and a wedge block, and means passing through said member, said brace and said block operable for effecting clamping engagement of said parts with a rail; said latter means being arranged for causing movement of said parts for adjustably positioning the rail on its support. 90

6. In a device of the class described, in combination, a wedge block having two parallel inclined plane surfaces for co-operating with a rail brace. 100

7. In a device of the class described, in combination, a rail brace having a portion adapted to contact a rail web and having two parallel inclined faces for cooperating with a wedge block. 105

8. In a device of the class described, in combination, a clamp tie plate and a rail brace movable thereon, a wedge block for moving said brace, and means passing through said brace and block for varying the position of said block with respect to said brace. 110

9. A rail clamp, including in combination, a member adapted for engaging a rail support, a rail brace, and a wedge block, and means passing through said brace and co-operating with said block for causing clamping engagement of said parts with the rail and the supporting member. 115

10. A rail clamp comprising, in combination a plurality of relatively movable members, certain of said members being in contact along a plurality of parallel surfaces inclined to the horizontal, and means co-operating therewith for effecting wedging action of said parts. 120

11. An adjustable rail clamp, including in combination, a tie plate having shoulders near each end thereof, a rail brace, a wedge block, said block being interposed between 130

said brace and one of said shoulders, and means for moving said block to cause engagement of said brace with a rail, said brace and block having a plurality of co-operating surfaces which are parallel and in planes inclined to the horizontal and intersecting the plane of the tie plate in lines parallel to the track rail.

12. Adjustable rail clamps, including in combination, a plurality of tie plates adapted to underlie a rail, said plates having shoulders near each end thereof, rail braces adapted to be placed on and moved along said plates, said braces having a plurality of surfaces inclined to the horizontal and in parallel planes, wedge blocks having similarly inclined surfaces interposed between a plate shoulder and a brace with the inclined surfaces in contact with the similar surfaces of the brace, and means for actuating said blocks for moving said braces into clamping engagement with a rail.

13. Adjustable rail clamps, including in combination a plurality of tie plates adapted to underlie a rail, said plates having shoulders near each end thereof, rail braces adapted to be placed on and moved along said plates, said braces having a plurality of surfaces inclined to the horizontal and in parallel planes, wedge blocks having similarly inclined surfaces interposed between a plate shoulder and a brace with the inclined

surfaces in contact with the similar surfaces of the brace, and means for actuating said blocks to cause movement of said braces to effect lateral movement of a rail.

14. A rail clamp for securing rails to ties, including in combination, a plate having shoulders near each end thereof, a rail brace member having a portion adapted to rest against a track rail and another portion provided with a plurality of inclined surfaces which are parallel but in different planes and which planes intersect the plane of the tie plate in straight lines parallel to the track rail, and a wedge block having similarly inclined surfaces for co-operating with the inclined surfaces of the brace and a portion adapted to abut one of the shoulders on said plate for urging the rail toward the other shoulder under certain conditions.

15. A rail clamp, including in combination, a brace having a plurality of parallel surfaces which are in planes inclined to the horizontal and which intersect the plane of the rail base in lines parallel to the rail base, a wedge block having similarly inclined surfaces for co-operating with the brace, and means for moving said block to cause engagement of said brace with a rail for clamping purposes.

Signed at Chicago, Illinois, this 23rd day of February, 1922.

RICHARD D. GALLAGHER.
